UNITED STATES PATENT OFFICE.

FREDERICK C. DUNHAM, OF FLEMINGTON, NEW JERSEY.

DUMPING-CAR.

SPECIFICATION forming part of Letters Patent No. 695,803, dated March 18, 1902.

Application filed October 12, 1901. Serial No. 78,444. (No model.)

To all whom it may concern:

Be it known that I, FREDERICK C. DUNHAM, residing at Flemington, in the county of Hunterdon and State of New Jersey, have invented 5 a new and useful Improvement in Dumping-Cars, of which the following is a specification.

My invention relates particularly to the method of opening and closing the doors on 10 dumping-cars, and more especially on railroad coal, ore, or other cars that are equipped with folding or swinging doors applied to a hopper.

When cars are loaded and the doors of hopper are sustaining the weight of material on 15 them, the doors open very suddenly when the fastenings are released, as the load is usually from two to four tons. If a wrench is used 20 on the winding-shaft for the purpose of opening the doors, the operator is liable to injury from the rapid movement of the wrench.

The main object of my invention is to avoid 25 this liability of accident. For this purpose I have invented a ratchet-wheel which is to be substituted for the ordinary ratchet-wheel, and which can be operated by a round bar of iron instead of a special wrench, and is described in the drawings annexed hereto, they being a part of this specification.

30 Figure 1 is a side elevation of a coal-car with the device attached in its position; Fig. 2, a detached elevation of a dumping device with the doors closed; Fig. 3, same as Fig. 2 with the doors open. Fig. 4 is an enlarged front 35 view of ratchet-wheel. Fig. 5 is a side view of the ratchet-wheel.

Similar letters refer to similar parts in the several views.

In gondolas or open cars with a drop bottom 40 the power is usually applied to a winding-shaft for operating the mechanism which opens and closes the doors. The end of this shaft is shown at A in Fig. 1, and the body of the car is designated by letter B, under 45 which is the hopper C. The winding-shaft A is mounted in bearings, which are usually attached to the sills b, one on each side of car, and the winding-shaft running transversely across and extending through the sides of car 50 and having a crank-arm D secured to shaft near the bearings. The outer end of crank D is connected to a set of levers or links E

and E' by a pitman or hinged joint, and the opposite end of levers E and E' are connected to the doors F and F' at m by a hinged joint 55 also. When the winding-shaft A is revolved, the opening made by the doors F and F' is governed by the length of crank D. The winding-shaft A is generally provided with a square shank on one of its outer ends, upon 60 which is fixed a ratchet-wheel which turns with the shaft. Outside the ratchet-wheel the square shank is extended sufficiently for a wrench to be applied.

To secure the doors F and F' from opening 65 while the car is in transit, a pawl G is hinged to the side of car-body B in a position that will allow its outer end to engage the notches or teeth in ratchet-wheel. Thus the turning of winding-shaft A cannot occur until the 70 pawl G is thrown out of engagement with ratchet-wheel.

All of the above is in general use, and no claim is made for any part of same being new.

In place of the ratchet-wheel (which is generally furnished with a series of notches all around its outer periphery) I have applied the wheel W, which is shown detached in Figs. 4 and 5. This wheel is shown with two notches in its periphery at c and c', the former being in position to secure the shaft A from turning and the doors F and F' closed when the pawl G is engaged with it. When the pawl is engaged with the notch c', the doors are then partly open. When the pawl 85 G is thrown back, the shaft A will turn until the cranks D hang perpendicularly, and the doors F and F' will open or drop downward as the shaft revolves. Upon the face of the wheel W and projecting outward from same 90 is a round pin or fulcrum, as shown at d, Figs. 4 and 5. This pin is strengthened part of its length by an inclined web f, the web projecting about one-half of the length of the pin. On the same face of wheel W is another rectangular protuberance g, about one-half the length of the pin d, with webs k and k' on each side of same and extending part of the way around the wheel W. Instead of having the square shank on the shaft A extend outward beyond the wheel W a thin collar or head is forged on shaft to secure the wheel W from coming off the shaft, so that there is nothing to prevent a lever e from be-

ing applied, as shown in Figs. 2 and 3, and the pin *d* used as a fulcrum for same, the projection *g* acting as the weight to be lifted. When the doors are opened, by turning the 5 shaft *A*, as in Fig. 2, the lever cannot be applied to secure a purchase in any other way than as shown, as the webs or ribs *k* and *k'* prevent the projection *g* from use as a fulcrum. The pin *d* being longer than the projection *g* and the web *f* extending half the 10 length of the pin necessitates the lever being applied in an oblique manner and not parallel with the body of the car. When the doors 15 *F* and *F'* are started and the weight of the load revolves the shaft rapidly, the lever is retained in the hands of the operator and is entirely loose from the shaft *A* or wheel *W*. Should it be held in close proximity to the 20 wheel *W* as it revolves, the web *h* would strike the lever and crowd it away from the wheel *W*. To close the doors *F* and *F'*, the lever is applied as shown in Fig. 3, again using the pin *g* as a fulcrum, and by a downward pull the motion is reversed, turning 25 shaft *A* and closing the doors. If the distance traveled by the outer end of lever be greater than the operator can conveniently pull, the pawl *G* can be dropped and engaged in the notch *C'*, leaving the door partly open. 30 Any piece of iron of reasonable length can be used to open or close the doors instead of a special wrench being provided, which is a matter of economy, and the question of safety to the operator is eliminated, as the danger 35 is done away with.

Having thus described my invention, what I claim, and desire to secure by Letters Patent, is—

1. A dumping-car with a winding-shaft in combination with a ratchet-wheel, a fulcrum 40 and web formed with the wheel and a projection *g*, on the face of said wheel.

2. A dumping-car with winding-shaft *A* in combination with a ratchet-wheel *W* having on its surface a fulcrum *d*, strengthened by 45 web *f* and a projection *g* with webs *k* and *k'* substantially as described and for purposes set forth.

3. A ratchet-wheel *W* for dumping-cars having on its outer surface a projecting pin *d* 50 with web *f* inclining from the face of wheel to one-half the length of pin, in combination with the projection *g* and the webs *k* and *k'* inclining from face of wheel to the same length as projection *g*, as and for the purposes specified.

4. A ratchet-wheel *W* with two notches *c* and *c'* in its outer periphery in combination with the fulcrum *d* and its inclined web *f* and the projection *g* with the inclined webs *k* and *k'* on each side of same, substantially as described.

In testimony whereof I have signed my name to this specification in the presence of two subscribing witnesses.

FREDERICK C. DUNHAM.
